UNITED STATES PATENT OFFICE.

SHERWOOD J. LARNED, OF CHICAGO, ILLINOIS, ASSIGNOR TO WESTERN ELECTRIC COMPANY, OF CHICAGO, ILLINOIS, A CORPORATION OF ILLINOIS.

TOLL APPARATUS FOR TELEPHONE-EXCHANGES.

No. 926,199.

Specification of Letters Patent.

Patented June 29, 1909.

Application filed July 7, 1902, Serial No. 114,570. Renewed April 3, 1905. Serial No. 253,626.

To all whom it may concern:

Be it known that I, SHERWOOD J. LARNED, citizen of the United States, residing at Chicago, in the county of Cook and State of Illinois, have invented a certain new and useful Improvement in Toll Apparatus for Telephone-Exchanges, of which the following is a full, clear, concise, and exact description.

My invention relates to telephone toll apparatus, and is applicable more particularly to systems wherein the mechanism of a toll device at the substation is controlled by a switch at the central office, actuated in the course of a connection between the line in question and another line.

The object of my invention is to provide an improved organization of circuits and apparatus by which a toll device may be operated automatically in taking down the temporary connection at the central office switchboard.

In a patent to Albert M. Bullard, No. 665,874, dated January 15th, 1901, there is described a toll line system in which a toll box is provided at the substation for receiving coins, the deposit of a coin being necessary in order to signal the central office. In that system the final disposition of the coin in the toll box is dependent upon the actuation by the operator of certain manual keys—that is to say, one key when depressed causes the coin at the substation to be thrown into the cash box, while the depression of the other key causes said coin to be released from the toll box and thrown into a return cup.

By means of my invention I am enabled to dispense with one or both of the manual keys at the central office, and to cause the automatic actuation of the toll device as incident to the mere opening of the operator's connection-switch—that is, the disconnecting of the operator's movable conductor or plug circuit. In a very large percentage of the calls, the connection desired by the subscriber calling is obtained, making it necessary for the coin in the toll box to be thrown into the cash box. Heretofore it has been necessary for the operator in each case to press a special button to deposit the coin, but by means of my invention the deposit of the coin is brought about automatically by the mere opening of the connection switch—that is, by the withdrawal of the plug from the springjack.

If desired, both of the alternative actions of the substation toll device may be brought about by the actuation of a single switch, which may be the automatic switch above referred to, at the central office, a switch being provided at the substation to be operated by the subscriber, which will coöperate with the central office switch in the control of the toll device, the effect produced upon the toll mechanism by the actuation of the central office switch being determined by the condition of the substation switch. A signal may be provided at the central office to inform the operator of the condition of said substation switch, so that the operator may know what action will result from an operation of her switch. For example, the substation toll device may have a polarized magnet with mechanism controlled thereby adapted to make alternative dispositions of a deposited coin according to the direction of the exciting current, the application of such current being controlled by a central office switch, which may be actuated automatically in withdrawing the plug from the springjack of the line in question. A reversing switch arranged to be operated by the lever of the usual gravity telephone switch may control the connection of the polarized magnet with the line, so that when the central office switch is opened the polarity imparted to said magnet, and consequently the operation of the toll device, will depend upon the condition of the said reversing switch. The ordinary supervisory signal in the plug circuit will inform the operator of the condition of the substation telephone switch. To return the coin, the operator would ask the subscriber to keep his telephone off the hook, and would then pull out the plug, whereby the toll device would be automatically actuated to throw the coin into a return channel. But ordinarily the operator would wait to pull out the plug until the subscriber had replaced his telephone on its hook, as at the end of a conversation, so that the deposit of the coin would be automatically effected upon the taking down of the connection.

I will describe my invention more particularly by reference to the accompanying drawing, in which—

Figure 1 is a diagram illustrating a telephone line extending from a substation to a

central office, with a portion of the central office switching apparatus, the system being organized and equipped for the automatic actuation of the substation toll device in accordance with my invention; and Fig. 2 is a diagram showing a substation apparatus wherein the connection of the polarized magnet of the toll device with the line is controlled by contacts operated by the telephone switch.

10 The same parts are designated by the same reference characters wherever they are shown.

The telephone line extends in two limbs 1 2 from the substation A to the line springs a' a^2 respectively of the terminal springjack a . The third contact or test ring a^3 of the springjack is connected to earth as usual by a conductor 3 which includes the winding of a 20 cut-off relay c , said cut-off relay being excited when connection is made with the line, by current applied to the test ring through a conductor 9 leading from the free pole of a battery b to the third contact of the operator's switch plug. The limb 1 of the telephone line is extended through the normal contacts of relays c and e to the free pole of grounded battery b .

The usual telephone apparatus is provided 30 at the substation, together with a toll box, which may be of the type shown in the patent to Bullard, No. 665,874, aforesaid. The toll box is provided with a coin-chute for receiving coins, and electromagnetic distributing mechanism for controlling the disposition of deposited coins. The coin-distributing magnet g is polarized and adjusted to respond only to current of a given electro-motive force—for example, 110 volt current. 40 Contacts f' f^2 are arranged to be closed together by a coin held within the coin-chute f , said contacts controlling a ground branch 4 from the line conductor 1, said branch including the winding of the polarized magnet g . A valve g^2 is controlled by the armature g' of the polarized magnet. Normally the valve stands in a position to arrest a coin within the chute, in which position the contacts f' f^2 are closed together by the coin. 50 When 110 volt current is applied at the central office to the line conductor 1, the armature g' of the magnet g is tilted to one side or the other, according to the direction of such current, so moving the valve to one side or the other and throwing the coin either into the cash box or into the return chute. For example, positive current applied to the line conductor 1 will cause the coin to be thrown into the cash box, while negative current applied to said conductor will cause the coin to be thrown into the return chute.

The central office operator is provided with the usual plug circuit for making temporary connection with the line at the springjack. 60 This plug circuit is well known and needs no

particular description. A key k is provided in association therewith, said key being adapted when depressed to connect the tip of the answering plug l with a grounded source G of negative 100 volt current, so that when 70 said key is depressed, the magnet of the toll device at the substation of the line with which the plug is connected, is excited by the negative current flowing out over the line conductor 1 to earth through the branch 4, 75 whereby the armature of said magnet is tilted in a direction to throw the previously deposited coin into the return chute. It is intended that the key k shall be actuated by the operator to return the coin only when the 80 desired connection cannot be obtained, as when the line called for is busy. Ordinarily, however, the connection desired will be made, and in this case the operator is relieved from the necessity of pressing a key to deposit the 85 coin, as has been required heretofore. I provide an automatic switching mechanism for momentarily applying positive 110 volt current from the generator G' to the limb 1 of the line, the application of the current preferably being controlled by the withdrawal of the answering plug l .

The cut-off relay c is provided with two armatures c' c^2 , one of said armatures controlling the extension of the line conductor 1 95 through the line relay d to the free pole of the grounded central battery b , and the other armature c^2 controlling a local circuit 6 from said battery b through a special relay e . Said special relay is constructed to act very sluggishly; for example, its armature may be made very heavy so as to have considerable inertia. The armature and back contact of said special relay e are arranged to control the extension of the line conductor 1 between the line relay d and the battery, and a front contact is provided for said relay e , connected by a conductor 5 with the generator G' . In other words, the relay e is adapted when excited to disconnect the battery b from the extension of line conductor 1 and connect said extension instead to the generator G' . The application of the current from either source to the line conductor 1 of the telephone line is, however, dependent 110 upon the closing of the contacts of the cut-off relay.

While for convenience of illustration two batteries marked b are shown in the drawing, it will be understood that the same may be a 120 single central battery connected as indicated.

The operation of the system is as follows: A subscriber who desires an exchange connection signals the central office by depositing a coin in the coin-chute f of his toll box, 125 and removing his telephone from his hook. The circuit of the central battery b is thus completed by way of the armature and back contact of relay e through the magnet of the line relay d , and by the way of the back con- 130

tact of relay c and armature of said relay, to the line conductor 1 of the telephone line and thence to earth by way of the grounded branch 4, which has been closed at the contacts $f' f^2$, and which includes the windings of the magnet g . The magnet g is not affected by this battery current, but the line relay is excited and draws up its armature, thus causing the display of the subscriber's line signal c^3 . The operator responds to the call as usual by inserting her answering plug l in the springjack of the calling line, and having obtained the number of the subscriber wanted, completes the connection by inserting the other plug of the pair into the springjack of the called line. If the desired connection, however, cannot be obtained, or if for any other reason the coin should be refunded to the subscriber, the operator 20 presses her key k , whereby negative 110 volt current from the generator G is applied to the line conductor 1 by way of the tip of the answering plug, whereby the magnet g of the toll device is energized and causes the 25 coin to be released and thrown into the return chute. But in most cases the connection will be made and the coin will be automatically deposited when the answering plug is pulled out of the springjack at the end 30 of the conversation, after the usual disconnect signal has been given. When the plug is first inserted in the jack, as in answering the call, the cut-off relay c is excited by current in the circuit 3 applied by way of the 35 sleeve or third contact of the plug, which registers with the test ring a^3 of the springjack. Both armatures $c' c^2$ of the cut-off relay are drawn up, and the connection of the line battery and line relay cut off. The 40 local circuit 6, including the special relay e , is closed by the cut-off relay during the connection, so that the generator G' is connected with the extension of the line conductor 1 leading from the back contact anvil of armature c' of the cut-off relay. The relay e , being slow to act, however, the generator current is not applied to the extension of the conductor 1 until the circuit of said conductor has first been broken by the separation 45 of armature c' of the cut-off relay from its back contact when, upon the insertion of the answering plug l , a circuit 9-3 is completed for said relay. When, however, at the end of the conversation the operator 50 pulls out the plug, the cut-off relay is de-energized and allows its armatures $c' c^2$ to fall back. The armature c' connects the line conductor 1 with the extension leading to the armature of the sluggishly-acting relay e before said armature has broken connection with the generator G' , so that for a 55 moment current from said generator is applied to the line conductor 1 and serves to actuate the polarized magnet g of the substation toll device, whereby the coin in the

chute is released and directed into the cash box. The deposit of the coin in the cash box is thus automatically accomplished by merely taking down the connection at the central office.

In Fig. 2 I have illustrated a modified substation circuit in which the connection of the polarized magnet g in the branch 4 is controlled by the contacts of a reversing switch k^3 operated by the lever k' of the telephone hook. A plunger k^2 is carried by said lever and is arranged to engage the springs of the reversing switch, which are connected with the terminals of the magnet g , and force said springs against outer contacts which form 70 the terminals of conductor 4. When the telephone is removed from the hook, the switch lever is raised and the plunger is withdrawn, permitting the switch springs to separate from their outer contact anvils and engage 75 inner anvils which also form terminals for conductor 4, but which are reversely connected with respect to the outer anvils. When the telephone is on the hook, the magnet g is so connected in the circuit of conductor 4 that current from generator G' applied to the line conductor 1 will impart to 80 said magnet a polarity such that the armature g' will be tilted in a direction to deposit the coin in the cash box. But when the telephone is off the hook the connections of magnet g are reversed, so that current from said 85 generator G' will cause an opposite movement of said armature, to throw the coin into the return channel.

When the substation is equipped after the plan of Fig. 2, then, the key k and generator G at the central office may be dispensed with, the actuation of the toll device from the central office being brought about automatically by the withdrawal of the plug, whether the coin is to be returned or deposited. If it is to be returned, the operator requests the subscriber to keep his telephone off the hook, and then she pulls out the plug, and so 100 brings about the application of current to the magnet g in the proper direction. Ordinarily, however, she will wait until both subscribers have hung up their telephones, and then when the supervisory signals indicate 105 this condition she will pull out the plugs, whereby current will be applied to magnet g in proper direction to cause the deposit of the coin in the cash box.

The supervisory signals which indicate the 110 condition of the substation switch may be of the usual character. I have shown a standard plug circuit, in which the central battery is connected in a bridge of the link conductors 7 8 between the windings of a repeating 115 coil. A supervisory relay is included in one of the link conductors in the path of current from said battery b controlled at the substation telephone switch, and said relay controls 120 a shunt about the subsidiary lamp signal h' 130

which is included in the conductor 9 extending from the free pole of the battery to the sleeve contact of the answering plug.

It will be understood that my invention is capable of embodiment in systems or apparatus differing considerably from the form herein specifically described and shown, and I do not wish to be understood as limiting myself to that particular embodiment, as modifications may readily be made to secure the same results by equivalent mechanical and electrical means.

Having thus described my invention, I claim:

1. The combination with a telephone line extending from a substation to a central office, of a toll device associated with the line, a springjack for the line, a plug and plug circuit for making connection therewith, a source of current adapted to operate said toll device, and automatic switching mechanism controlled by said coöperating plug and springjack and operated in the separation thereof to momentarily connect said source of current with the line; whereby the toll device is automatically operated.

2. The combination with a telephone line extending from a substation to a central office, of a magnet connected with the line at the substation, a connection terminal for the line at the central office, a connection switch adapted for engagement with said terminal, a source of current adapted to excite said magnet, a slow-acting relay *e* controlling the connection of said source of current to the line, a quick-acting relay *c* controlling the line circuit between the relay *e* and the substation, and circuits for exciting both relays established during the closure of the connection switch, whereby the substation magnet is momentarily excited when the connection switch is opened.

3. The combination with a telephone line extending from a substation to a central office, of a toll device at the substation having a polarized magnet and alternative mechanism operated thereby, a reversing switch at the substation controlling the connection of said magnet with the line, a connection terminal for the line at the central office, a connection switch for engagement therewith, a source of current for exciting the substation magnet, and switching mechanism controlled in the operation of the connection switch adapted to apply said source of current to the line, whereby said connection switch and reversing switch cooperate in the control of the said alternative mechanism.

4. The combination with a telephone line extending from a substation to a central office, of a toll device at the substation having a polarized magnet and alternative mechanism operated thereby, a reversing switch at the substation controlling the connection of said magnet with the line, a connection

terminal for the line at the central office, a connection switch for engagement therewith, a source of current for exciting the substation magnet, a signal at the central office controlled in the operation of the substation reversing switch to indicate the condition of said reversing switch, and switching mechanism controlled in the operation of the connection switch adapted to apply said source of current to the line, whereby either alternative action of the said alternative mechanism at the substation may be effected automatically from the central office.

5. The combination with a telephone line extending from a substation to a central office, of a toll device at the substation having a polarized actuating magnet, alternative mechanism operated thereby, and a reversing switch at the substation controlling the connection of said magnet with the line, a signal at the central office, and means for displaying the same controlled in the movement of said switch, to indicate the condition thereof, a source of current at the central office, and a switch for applying current to the line to excite the magnet of the toll device.

6. The combination with a telephone line extending from a substation to a central office, and a telephone switch controlling the circuit of the line, of a springjack for the line at the central office, a plug and plug circuit for making connection therewith, a toll device at the substation having a polarized actuating magnet, alternative mechanism operated thereby, a reversing switch at the substation controlling the connection of said magnet with the line, means for operating said switch actuated in the movement of said telephone switch, a signal at the central office adapted to indicate the position of said switch, a source of current at the central office, and an automatic switch actuated in the withdrawal of said plug from its springjack, for applying current to the line to excite the magnet of the toll device.

7. The combination with a telephone line and its switch terminal, of a switchboard connector adapted for temporary engagement therewith, a toll device at the subscriber's station, associated with said line, a source of current for actuating said toll device, and automatic switching mechanism controlled by the coöperating connector and line terminal to be closed in the separation thereof, and connected to apply said source of current to said toll device when so closed.

8. The combination with a telephone line and its springjack, of a plug and plug circuit for making connection therewith, a toll device associated with the line, a source of current, a switch controlled by the inserted plug and closed in the withdrawal of said plug, and a source of current under the control of said switch, to be applied thereby to said toll device; whereby the toll device is

unaffected by the insertion of the plug, but is automatically actuated upon the withdrawal thereof.

9. The combination with a subscriber's telephone line and its switch terminal, of the central office connector for engagement therewith, a toll device at the subscriber's station, associated with said line, a source of current for actuating said toll device, automatic switching mechanism controlled by the coöperating connector and line terminal to be closed in the separation thereof, for applying current to said toll device, and means arranged to determine the actuation of said toll device by said automatic switching mechanism.

10. The combination with a subscriber's telephone line and its springjack, of the central office operator's plug and plug circuit, a toll device connected with the line adapted for alternative operation, automatic mechanism actuated by the withdrawal of the plug from the springjack, adapted to determine one operation of said toll device and means adapted to determine the alternative operation of said toll device.

11. The combination with a subscriber's telephone line and a toll device at the substation thereof, of a central office springjack for the line, a plug and its plug-circuit for making connection therewith, a source of current for actuating said toll device, a switch *c'*, means, actuated upon the insertion of said plug, to open said switch, and upon the withdrawal of said plug, to close said switch, and electromagnetic switching mechanism actuated in the insertion of the plug adapted to bring the source of current under control of said first mentioned switch; whereby the current is automatically applied to the line to actuate the subscriber's toll device when the plug is withdrawn from the springjack after a connection.

12. The combination with a telephone line and its switch terminal, of a switch connector adapted for temporary engagement therewith, a toll device at the subscriber's station, associated with said line, and means operated in the separation of said switch

terminal and connector adapted to effect the operation of said toll device.

13. The combination with a telephone line and its switch terminal, of a switch connector adapted for temporary engagement therewith, a toll device at the subscriber's station, associated with said line, a circuit for said toll device, and automatic switch mechanism in said circuit operated in the separation of said switch terminal and connector adapted to effect the operation of said toll device.

14. The combination with a telephone line and its switch terminal, of a switch connector adapted for temporary engagement therewith, a toll device at the subscriber's station, associated with said line, a circuit for said toll device, and switch mechanism in said circuit momentarily operated in the separation of said switch terminal and connector adapted to effect the operation of said toll device.

15. The combination with a telephone line and its switch terminal, of a switch connector adapted for temporary engagement therewith, a toll device at the subscriber's station, associated with said line, a circuit for said toll device, and means operated in the separation of said switch terminal and connector adapted to affect said circuit to actuate said toll device.

16. The combination with a telephone line and its switch terminal, of a switch connector adapted for temporary engagement therewith, a toll device at the subscriber's station associated with said line, automatic mechanism operating in the separation of said switch terminal and connector to effect the actuation of said toll device, and means associated with the switch connector to determine the operation of said automatic mechanism.

In witness whereof, I hereunto subscribe my name this 29th day of May A. D., 1902.

SHERWOOD J. LARNED.
